UNITED STATES PATENT OFFICE

2,599,235

CONCRETE CONVEYING APPARATUS

Robert Lee Coney, Levittown, N. Y., assignor to
 The Prehy Co., Incorporated, New York, N. Y.,
 a corporation of New York

Application September 7, 1950, Serial No. 183,569

1 Claim. (Cl. 302—53)

1

My invention relates to improvements in the design and operation of pneumatic pressure grouting equipment especially in terms of the flow of materials through the discharge system of the equipment.

In present practice a pressure grouting machine usually comprises a pressure tank, a pressure-tight valve for charging grouting material to the tank, a discharge opening and valve in the tank in releasable connection with a flexible or portable delivery tube and means for delivering air pressure to the tank. The air pressure fed into the tank forces the grout out at considerable velocity through the discharge opening and delivery tube to the working area. Pressure grouting is used with great advantage to convey and compact mortar, concrete aggregate or inert material mixtures through light flexible hose or pipe lines into otherwise inaccessible places above or below ground. For example, in many instances the heavy costs of cofferdams can be avoided or the pumping and hoisting of large amounts of materials can be eliminated. Pressure grouting provides pressure injection of mortar compositions of optimum water content, assuring strength and permanency and eliminating the cost and disadvantages of handling surplus water. Although pressure grouting equipment theoretically appears quite flexible in terms of the mortar and concrete compositions which can be handled, it is now well known that pressure grouters suffer the serious disadvantage of limitation in operation to a relatively narrow range of particle sizes. Thus pressure grouters generally employ a cone discharge to which a 2-inch pipe coupling is welded. The 2-inch coupling provides a connection for attachment of the discharge valve and delivery hose. In normal operations, 1 1/4-inch delivery hose is employed so that a 2-inch by 1 1/4-inch reducer must be provided in the end of the discharge connection. Where relatively large aggregates are to be handled, e. g. material containing about 1/4-inch stones, the 2-inch delivery hose is employed. There are many cases, however, when it is necessary or highly desirable to handle compositions requiring the use of smaller or larger delivery hoses for efficient operation.

I have found that discharge of grouting mixtures, particularly the more plastic cementitious mixtures, is very significantly affected by any restrictions in the line of flow. In addition to the flow irregularities and plugging difficulties developed as larger aggregates are employed, restriction in the flow path where the smaller delivery hose sizes are employed tends to cause such severe

2

friction that only materials of the thinnest consistency of mix can be handled. According to my invention, I provide means for simply and quickly effecting smooth and unrestricted discharge flow from pressure grouting apparatus under a wide range of conditions using discharge lines of varying sizes.

My invention provides, in combination with the usual pressure tank and air pressure means, 10 a conically tapered lower section for the tank which has a bottom opening of larger diameter than the ultimate discharge opening. A second removable conical section is then provided so as to coincide in angle of slope with the first section and which has a discharge opening coinciding with the internal diameter of a delivery hose or tube selected for the specific job requirement. Further, I also provide means for releasably attaching the second conical section to the first conical section in pressure-tight engagement, to make the second section easily removable so as to insure interchangeability of different size cones, and so constructed as to effect a smooth path of unrestricted flow from the tank through the discharge opening and delivery tube. Thus the lower discharge conical section can be readily and quickly disengaged in the field and replaced with an auxiliary section sized and equipped with discharge fittings adapted to fit the actual job specifications. The necessity of attempting to get by with trouble-causing flow restrictions in the discharge section and fittings of the grouting apparatus or by use of discharge hose of insufficient internal diameter is avoided. At the same time, 30 maintenance of the grouting apparatus is vastly improved. Inspection and cleaning of the lower tank and the discharge piping is greatly facilitated by employment of the detachable bottom cone section.

40 My invention is illustrated in the accompanying drawings in which Figures I and II represent a side elevation, partly in section, of a pressure grouting machine incorporating my invention, and in which Figure III represents an overhead 45 plan view of the pressure grouting machine. According to the embodiment shown the main portion of the material tank is cylindrical and is vertically positioned. In the drawings, a cylindrical welded tank 10 is shown equipped with a manually operated bell valve 11 at the top of the tank for loading. The bell valve 11 seats in funnel-shaped member 12 and is operated by a hand lever 13 and connecting shaft 14. The tank 10 is provided with an attached lower conical section 50 15 terminating in a lower discharge opening of

relatively large diameter. As shown, conical section 15 is provided with circular flange 16 which is adapted to engage with the flange 17 of a second conical section 18 which coincides in angle of slope with conical section 15. Pressure-tight attachment of the two conical sections is effected by means of gasket 19 and bolts 20. While flange 16 may be affixed to section 15 by welding, the lower detachable cone 18 is advantageously cast in one piece. In this way the internal radii 20a will be smoothly shaped to insure even flow of the grout without excessive friction on this part of the machine. The flanges are drilled and tapped to receive the number of studs required by the A. S. M. E. code for unfired pressure vessels. The lower conical discharge section 18 is provided with a discharge connection 21, advantageously cast as an integral part of section 18, to which is attached discharge valve 22 and piping elbow or adapter 23 for attachment of delivery hose 24. According to my invention a series of lower discharge sections 18 having various diameter discharge openings is provided so that with appropriately selected discharge valves, piping and delivery hoses, a smooth and unrestricted discharge path of flow is provided in cooperation with the lower conical section 15 of the cylindrical tank 10. The discharge valve 22 may be manually operated as by lever 25 and connecting link 26.

The cylindrical tank 10 is equipped with an internal vertical by-pass pipe 27 having flexible discharge fitting 28 and so mounted so that it can be firmly seated over the discharge opening or can be raised clear of the discharge opening by means of lever shaft 30 and lever handle 31. In the low position of the by-pass pipe the air current by-passes the material in the tank and enters directly into the discharge line with full force to test and ascertain the conditions for the reception of the grout in narrow fissures or passages and to free the discharge line of any possible obstruction. When the by-pass pipe is lifted off its seat the material enters the discharge line to be propelled by the kinetic air pressure to its destination. Air pressure is provided to the tank through line 32. The inlet air is passed through T 34 to which is connected air pressure gauge 35, lines 36 and 37 and flexible hose 38 to the top of by-pass pipe 27. Manually controlled valve 39 is provided for control purposes in line 37. Air is delivered to the top of the tank through valve 40 and T 44. Exhaust connection 42 and manually operated valve 43 are connected to the air intake line through T 44. A pressure release safety valve 47 is provided. As shown, the cylindrical tank 10 and auxiliary equipment is mounted on a system of wheels 47a and leg 48.

In operation, the cylindrical tank 10 is loaded while valves 38, 45 and bottom discharge valve 22 are closed. The by-pass pipe 27 is lowered into seated arrangement over the discharge opening by raising lever handle 31. With the exhaust valve 43 open, the tank is filled to a level below the bell valve 11 with the properly prepared material. The discharge system is blown out by closing the exhaust valve 43 and closing the bell valve 11. The feed valve 46 is opened and pressure is put on the tank thereby sealing the bell valve 11. The by-pass valve 39 then is opened, followed by the discharge valve 22. For discharging, the valves remain in the same position as for by-passing but the by-pass pipe 27 is raised by depressing the lever handle 31, so that material can now enter the discharge system. The mate-

rial within the tank may be agitated without discharge by closing the discharge valve 22 and the feed valve 46, and by closing air valves 39 and 46. The exhaust valve 43 then is opened and when the bell valve 11 drops by-pass valve 39 is gradually opened admitting air through by-pass 27 as needed for agitation of the material in the tank 10.

According to my invention a smooth path of unrestricted flow is insured during the discharge operation by arrangement of one of the readily replaceable conical discharge sections 18 of selected discharge size in cooperative relationship with the conically tapered lower section 15 and an appropriately sized auxiliary discharge valve 22, elbow or other fitting 23 if desired, and delivery hose 24. The by-pass pipe 27 advantageously is fitted with a flexible rubber discharge fitting 28 of sufficient size to insure seating over the discharge openings of the various auxiliary conical sections 18. My invention, however, permits convenient change or replacement of this fitting. Also as shown, the by-pass pipe is fitted with a flattened rubber internal check valve 50 which is clamped in place between the lower end of by-pass 27 and discharge fitting 28. The flattened rubber valve 50 permits discharge of air from by-pass 27 but prevents back flow of material into by-pass 27 tending to clog the air system.

Although I have illustrated a pressure grouting apparatus in which the main portion of the material tank is cylindrical, it is not necessary to use a tank of this shape in the practice of my invention. For example, the lower attached conical section may be joined to a box shape or any other suitable material tank. Likewise the tank may be also positioned horizontally and ejection of grout aided in this position by use of internal paddles. Further, incorporation and use of a by-pass pipe in the apparatus embodying my invention as illustrated in the drawing is also optional.

I claim:

In a pressure grouting apparatus comprising a pressure tank having a conically tapered section with a bottom opening of larger diameter than the desired discharge opening; a pressure-tight valve mounted on said tank for charging grouting material to said tank; means connected to said tank for applying air pressure to the top of said material; a vertical by-pass pipe mounted in said tank and extending coaxially into said conically tapered section; means for vertically moving said by-pass pipe; means for supplying air under pressure to and downwardly through said by-pass pipe; substitutable means for providing a smooth unrestricted passageway from said conically tapered section to a proper size delivery hose to provide the grouting apparatus with proper size predetermined discharge passageways for varying materials ranging from fine wet material to aggregate-containing wet material, said substitutable means including a conical discharge section having a top opening equal to the bottom opening of said conically tapered section and coinciding in angle of slope with said conically tapered section, said conical discharge section having a bottom discharge connection of a size equal to the selected proper size delivery hose, means for releasably attaching said conical discharge section to said conically tapered section in pressure type engagement to provide a smooth unrestricted passageway to the bottom discharge connection, and valve means connected to said bottom discharge connection adapted to receive the selected deliv-

ery hose; and a tubular flexible rubber fitting coaxially mounted on said by-pass pipe and depending therefrom, said flexible rubber fitting having a conically tapered bottom portion for abutting engagement with said conical discharge section upon downward movement of said by-pass pipe.
